UNITED STATES PATENT OFFICE.

WILLIAM HENRY CLING, OF CHARLESTON, SOUTH CAROLINA.

SHOE-LACE.

No. 813,949.

Specification of Letters Patent.

Patented Feb. 27, 1906.

Application filed March 10, 1904. Serial No. 197,805.

To all whom it may concern:

Be it known that I, WILLIAM HENRY CLING, a citizen of the United States, and a resident of Charleston, in the county of Charleston and State of South Carolina, have invented 5 certain new and useful Improvements in Shoe-Laces, of which the following is a specification.

The object of my invention is to provide 10 an attachment for ordinary flexible shoe-laces which will enable them to be easily tied or fastened in such manner that they will not become accidentally loosened or untied in ordinary use.

15 The attachment is constructed and applied in a manner hereinafter described, and illustrated in the accompanying drawings, in which—

Figure 1 is a view of the upper portion of a 20 laced high shoe having my improved lace applied thereto as in actual use. Fig. 2 is a plan view of my improved lace tied and formed as a bow, as used on ladies' low shoes. Fig. 3 is a view of the attachment 25 proper or the flexible wire having coiled ends, the lace proper being indicated by dotted lines. Fig. 4 is a view showing the lace fastened by twisting the end portions together, the ends of the lace proper being left free. 30 Fig. 5 is a view further illustrating the arrangement of the flexible wires when inter-linked or twisted together.

A indicates a stout and easily-flexible wire, which is applied to an ordinary shoe-lace at 35 points between its middle and end portions, the latter being left free. The wire A extends along the lace and is secured by coiling or twisting its ends around the lace, as indicated at B C. It will be noted that in the 40 preferred form of my invention the outer coil or twist B is located some distance from the end of the lace, so that a considerable portion of the latter is left entirely flexible and free. This feature has considerable 45 importance, since the ends of the lace have not only the ordinary appearance and hang pend-

ent, as usual, but they may be seized and subjected to traction for manipulating and fastening the lace, as shown and described, and in such operation there is practically no 50 traction on the wire A, and consequently its coils B C are not liable to slip or slide on the lace proper, as they would otherwise tend to do.

In practical use my improved lace is 55 formed of two parts or portions, one being a flexible lace, such as is in common use, and the other a flexible stiffening-wire. Such compound lace is applied to a shoe in the usual way, it being passed alternately or 60 from side to side around opposite hooks, and those portions of the lace of which the wire A forms a part are passed around the top hook and then twisted together or looped around each other, as shown best in Figs. 1, 4, and 5. 65

The ends of the lace being left free, the lace has a better appearance and simulates one of the ordinary kind. A lace provided with this attachment may be very easily and quickly tied or fastened and will not become 70 loosened or released as ordinary laces tend to do, especially by reason of the friction with the bottom edge of trousers or skirts. It is apparent that it may be instantly released or 75 unfastened by simply bending the looped or twisted portions in the direction reverse to that required for fastening it.

What I claim is—

The improved shoe-lace, comprising the flexible lace proper of ordinary construction, 80 and the flexible wire which is attached thereto, the ends B, C, of the wire being twisted tightly about the lace proper and the body of the said wire being extended along such lace between such points of attachment, and the 85 ends of the lace proper being left free, substantially as described.

WILLIAM HENRY CLING.
